UNITED STATES PATENT OFFICE.

JOHN KESTER TOMLINSON, OF PICKAWAY, WEST VIRGINIA.

FEED-WATER HEATER.

SPECIFICATION forming part of Letters Patent No. 678,800, dated July 16, 1901.

Application filed October 18, 1900. Serial No. 33,496. (No model.)

To all whom it may concern:

Be it known that I, JOHN KESTER TOMLINSON, a citizen of the United States, residing at Pickaway, in the county of Monroe and 5 State of West Virginia, have invented a new and useful Feed-Water Heater, of which the following is a specification.

This invention relates to feed-water heaters designed for heating feed-water prior to its 10 introduction into a steam-boiler, the object of the invention being to provide a construction wherein the exhaust-steam from the engine may be condensed and the water of condensation conveyed to a hot-well, from which 15 it may be pumped to the boiler, the water in its transit from the pump to the boiler being utilized to effect condensation of other exhaust-steam and being heated thereby.

Additional objects and advantages of the 20 invention will be evident from the following specification.

In the drawings forming a portion of this specification, and in which like numerals of reference indicate similar parts in the several views, Figure 1 is an elevation showing the heater and a portion of a boiler, the end of one of the drums of the heater being removed to show the structure of the drum. Fig. 2 is an elevation of the heater, taken at 25 right angles to Fig. 1, two of the drums and a portion of the base or trunk being shown in section.

Referring now to the drawings, the present heater comprises a preferably rectangular trunk 5, in one wall of which is formed a plurality of openings 6, with which communicate drums 7, which are cylindrical in form. Each of the drums comprises a shell having heads 8 and 9, and connecting which heads are 30 steam-tubes 10. The outer ends of these tubes 10 communicate with the dome 11 at the outer end of the drum beyond the head 9, this dome being formed by a hollow cap 12, engaged with a flange 13 at the end of the 35 drum, and which cap is held in place by means of a bolt 14 passed through both heads of the drum and through the cap, a nut upon the outer end of the bolt being adapted to impinge against the cap and hold the cap in 40 place.

Transversely of the trunk 5 are arranged

baffle-plates 16, which are disposed diametrically of the openings 6, so that the tubes of each drum lie half at one side of the adjacent baffle-plate and half at the opposite 55 side thereof, so that a circulation from the trunk may be had up one series of tubes into the dome 11 and back the other series into the trunk, and so on throughout the entire number of drums.

The trunk 5 is disposed vertical, as shown, and the drums extending at right angles thereto lie horizontal and parallel.

With the upper end of the trunk 5 is connected the exhaust-pipe 18 from a steam-engine, while at the lower end of the trunk is connected a common form of hot-well 19.

The drums 7 are connected alternately at opposite ends by pipes 20, which communicate with the inclosures of the shells between the heads 8 and 9 thereof, so that water may be forced into the lower drum at one end and will pass from the opposite end of the drum to the adjacent end of the next drum, will then pass longitudinally through this 75 second drum to its opposite end, and then out and to the next drum, so that there will be a zigzag circulation through the series of drums.

A pump 21 has a suction-pipe 22 connected 80 with the hot-well 19, while its discharge-pipe 23 is connected with the inlet end of the lowermost drum, and the uppermost drum is connected with the boiler 24, that is to be fed.

The steam-feed pipe 25 from the boiler 85 leads to a dome 26, from which leads a pipe 27 to the engine, and connecting the pipe 27 and the exhaust-pipe 18 is a branch pipe 28, including a safety-valve 29, which opens in the direction of the exhaust-pipe, so that any 90 steam that may be blown off will pass through the heater to be condensed and thence to the hot-well to be returned to the boiler. With this construction it will be seen that the steam which is exhausted, as also any steam 95 that may be blown off through the safety-valve, is utilized in the heater to heat the feed-water and is condensed and returned through the drums of the heater, where it is heated and from which it is forced into the 100 boiler.

The branch pipe 28 is provided with a con-

trolling globe-valve 30, by means of which the operation of the safety-valve at this point may be prevented.

It will be understood that in practice various modifications of the specific construction shown may be made and that any suitable materials and proportions may be used for the various parts without departing from the spirit of the invention.

10 It will of course be understood that the temperature to which the water is raised will within certain limits depend upon the number of drums employed.

What is claimed is—

15 1. A feed-water heater comprising a trunk divided into compartments, drums having tubes therethrough and disposed for the tubes thereof to communicate with different compartments, removable caps at the outer ends 20 of the drums to form domes connecting the tubes of their respective drums, a bolt passed longitudinally through each drum and its cap and having a nut for engagement with the cap for holding the latter in place, connections 25 between the drums exterior to the tubes, a pump having its suction-pipe connected with the trunk and having its discharge-pipe con-

nected with the lowermost drum, and a feed-pipe connected with the uppermost drum.

2. A feed-water heater comprising a trunk 30 including compartments, a series of drums having pipes therethrough, said drums being disposed for certain of their pipes to communicate with one of the compartments and the remaining pipes to communicate with a second compartment, caps for the outer ends of the drums forming domes with which the tubes communicate, a bolt passed longitudinally through each drum and the cap thereof and having a nut for engagement with the cap 40 to hold it in place, pipe connections between the alternate ends of the drums, a hot-well connected with the lower end of the trunk, a pump between the hot-well and the lower drum, a steam-exhaust pipe connected with 45 the upper end of the trunk, and a water-supply pipe connected with the upper drum.

In testimony that I claim the foregoing as my own I have hereto affixed my signature in the presence of two witnesses.

JOHN KESTER TOMLINSON.
